HENRY A. STRINGFELLOW AND ELLIS W. TEMPLIN, OF ROCHESTER, NEW YORK.

STEAM-ENGINE.

1,350,625.

Specification of Letters Patent. Patented Aug. 24, 1920.

Application filed October 11, 1915. Serial No. 55,172.

To all whom it may concern:

Be it known that we, HENRY A. STRINGFELLOW and ELLIS W. TEMPLIN, of Rochester, in the county of Monroe and State of New York, have invented certain new and useful Improvements in Steam-Engines; and we do hereby declare the following to be a full, clear, and exact description of the same, reference being had to the accompanying drawings, forming a part of this specification, and to the reference-numerals marked thereon.

Our present invention relates to steam engines and more particularly to engines of what is known as the "Una-flow" type where the admission of steam to the piston occurs at both ends of the cylinder while the exhaust occurs near the middle of the cylinder or at a point midway of the limits of travel of the piston and the invention has for its object to materially reduce the weight of the engine by shortening both the cylinder and the piston while preserving a given length of piston stroke; to permit the attainment of higher piston speeds and to increase the general efficiency of the engine by providing greater flexibility in the adjustment of the cut-off and by reducing the time during which the cylinder is subjected to exhaust temperature. To these and other ends the invention resides in certain improvements and combinations of parts, all as will be hereinafter more fully described, the novel features being pointed out in the claims at the end of the specification.

In the drawings:

Figure 1 is a longitudinal central section through the cylinder and admission valve of a steam engine constructed in accordance with and illustrating one embodiment of our invention, and

Fig. 2 is a transverse section taken substantially on the line 2-2 of Fig. 1.

Similar reference numerals throughout the several figures indicate the same parts.

The usual type of una-flow engine employs a heavy block piston which itself controls the central exhaust port. The cut-off face thereof is at some distance from the steam face and the added length of the cylinder required to accommodate it for the full stroke, together with the necessary size of the piston itself makes the aggregate weight and size excessive. In the practice of our present invention, we control the exhaust port independently of the piston by a

member separate therefrom and movable relatively thereto so that an ordinary disk piston can be used for the same stroke within a cylinder of approximately half the length. In the present embodiment of the invention, we have shown an engine designed more particularly for locomotive use and referring more particularly to the drawings, 1 indicates a saddle casting that supports the boiler and carries a cylinder 2 jacketed at 3 and having the jacketed heads 4 and 5, the cylinder and heads being enclosed by lagging 6. An exhaust belt 7 partly surrounds the center of the cylinder 70 on the outer side which belt is expanded on the inner side into an exhaust chamber 8. At the center the cylinder walls are pierced by a plurality of circumferentially arranged exhaust ports 9 that open into the belt and 75 into the chamber 8. There is thus provided, as shown in Fig. 2, a progressively enlarged passage for the escape of the exhaust steam as it accumulates from the various ports, while at the same time the cylinders are not 80 caused to project unduly and increase the width of the locomotive.

The live steam is admitted from the boiler through a passage 10 and manifold 11 to both ends of a cylinder 12 constituting a 85 valve chamber 13 and thence through intake ports 14 and 14^a to the opposite ends of the cylinder 2 under the control of an outside admission piston valve 15 having an operating rod 15^a or any suitable form of 90 valve may be used. The exhaust ports 9 are controlled by a reciprocating sleeve 16 of about half the length of the cylinder, which is in intimate contact with the walls of the latter and travels from one end to 95 the other, being so proportioned in length that it will uncover the exhaust port while at its limit of movement at either end. It is operated by the steam pressure acting on the exposed end of the sleeve and the 100 rods 17 passing through the cylinder head 5 and connected by a cross head 18 with an operating rod 19 which is connected at a suitable point in the valve gear and serves to synchronize the motion of the sleeve with 105 the motions of the other parts of the engine.

The piston 20 having the rod 21 may be of the ordinary disk type, as shown. At any rate, it is very short, much shorter than the sleeve 16 which latter it fits closely in 110 the manner of an ordinary piston and cylinder and it works in contact with the sleeve

instead of with the cylinder walls 2. The sleeve travels at approximately half the speed of the piston so that there is relative movement between them and the sleeve and 5 piston traverse the cylinder while the piston is traversing the sleeve. The operation is as follows:

In Fig. 1, the piston is shown ready to begin its stroke with the valve 15 retracted 10 to permit the admission of steam through inlet port 14 to the left hand face of the piston. The latter is at the left hand end of the sleeve and the sleeve is at the left hand end of the cylinder with the exhaust 15 ports 9 uncovered. The steam used on the previous stroke is being exhausted through the ports 9 which, because of their size and number, reduce the pressure very rapidly. Both the piston and sleeve now travel to 20 the right. The sleeve, though moving more slowly, closes the exhaust port 9 before the piston has reached the neighborhood thereof and by the time it has so completed its travel that it passes over these ports 25 and opens them again, the piston has reached the right hand end of the sleeve and the sleeve has reached the right hand end of the cylinder ready for an admission of steam at 14^a and repetition of the operation 30 from the other direction.

It is obvious that the compression of the exhaust steam is negligible, it being possible to design the parts so that it is trapped in front of the piston in small volume raised not 35 above boiler pressure at completion of the piston stroke. The exhaust virtually flows out freely and is not driven out by the piston. Other advantages, aside from the above mentioned reduction in weight and 40 size, are that the wear of the piston and sleeve is widely distributed at both sides of the sleeve, and renewal of the sleeve after wear compensates for wear of both the cyl-

inder surface and piston surface without changing either.

45

We claim as our invention:

1. In a steam engine, the combination with a cylinder and a piston operating therein, said cylinder being provided with inlet ports at each end and an intermediate 50 exhaust port, of a sleeve arranged to reciprocate in the cylinder between the walls of the latter and the piston and to open and close the exhaust port upon each reciprocation of the piston and additional 55 means for opening and closing the intake ports.

2. In a steam engine, the combination with a cylinder and a piston operating therein, said cylinder being provided with 60 inlet ports at each end and an intermediate exhaust port, of a sleeve arranged to reciprocate in the cylinder between the walls of the latter and the piston and to open and close the exhaust port with each reciprocation of the piston, means independent of the piston for operating the sleeve, and additional means for opening and closing the intake ports.

3. In a steam engine, the combination 70 with a cylinder and a piston operating therein, said cylinder being provided with inlet ports at each end and with an intermediate exhaust port at a point midway of the piston stroke, of a sleeve arranged to 75 reciprocate in the cylinder between the walls of the latter and the piston and to open and close the exhaust port upon each reciprocation of the cylinder, said sleeve being of a length approximating one half of that of the 80 cylinder.

HENRY A. STRINGFELLOW.

ELLIS W. TEMPLIN.
